UNITED STATES PATENT OFFICE.

HARRY C. SILLETT, OF KANSAS CITY, MISSOURI

HYDROCARBON-GAS GENERATOR AND BURNER.

1,427,129.

Specification of Letters Patent. Patented Aug. 29, 1922.

Application filed February 27, 1920. Serial No. 361,816.

To all whom it may concern:

Be it known that I, HARRY C. SILLETT, a citizen of the United States, and a resident of Kansas City, in the county of Jackson and State of Missouri, have invented certain new and useful Improvements in Hydro-carbon-Gas Generators and Burners, of which the following is a specification.

My invention relates to improvements in 10 burners of crude oil and the like, and it consists in the constructions, combinations and arrangements herein described and claimed.

One of the foremost objects of the invention is to provide a burner system which 15 comprises a hydro-carbon gas generator, burner, means whereby the crude oil which is employed may be instantaneously lighted, and an improved fuel tank including a part of the instantaneous lighting means.

20 A further object of the invention is to provide a multiple unit liquid fuel burner, embodying slide valve means whereby all of the units with the exception of one can be disconnected so that only one burner need be 25 used when thus required, with the result of effecting a saving in the consumption of fuel.

30 A further object of the invention is to provide a fuel oil burner which is capable of application to a stove insufficiently large to permit of centralizing the burners under the lids, in which circumstance, the intake of the burner is projected and secured to the outside of the stove instead of the inside.

35 Other objects and advantages will appear in the following specification, reference being had to the accompanying drawings, in which:—

40 Figure 1 is a diagram illustrating a double burner constructed in accordance with my invention, in connection with the improved fuel reservoir, more specifically described below,

45 Figure 2 is a detail side elevation of the improved burner structure,

50 Figure 3 is a detail sectional view of the burner intake at the right end of the structure in Figure 2,

55 Figure 4 is a detail view illustrating the intermediate slide valve, by means of which one of the burner units can be disconnected when desired,

Figure 5 is a detail cross section of the burner ring, illustrating a strengthening fin or rib on the inside,

55 Figure 6 is a plan view of a burner structure adapted to a gas range, portions of the

top of the range being broken away so as to reveal the burner structure,

Figure 7 is a longitudinal section taken substantially on the line 7—7 of Figure 6, 60

Figure 8 is a detail cross section of the slide valve between the range and oven part of the gas range, and,

Figure 9 is a detail sectional view illustrating how a stove lid may be "finned" on 65 the bottom side, in order to facilitate heat radiation.

A general survey of the operation may be introduced at this time in order to familiarize the reader with the manner of starting 70 the burner. A pair of burners 1 are joined by a conduit 2, the right end of which has a curved cap 3 hereafter known as the intake.

Supported over the conduit 2 by means of 75 plates 4, is a vaporizing pipe 5 which leads to the open end 6 of the intake 3, and is supplied by a suitable fuel oil from the reservoir 7 by means of a connecting pipe 8. This pipe 8 leads to one side of a valve body 9, where the flow of oil is controlled by 80 means of a valve 10. There is a somewhat similar valve 11 on the other side of the valve body 9, this valve however, controlling the flow of priming fluid from an auxiliary reservoir 12 inside of the main res- 85 ervoir 7.

A pipe 13 leads from the valve 11 to a U tube 14 inside of the auxiliary reservoir. There is a pressure of air above the liquids in the reservoirs 7 and 12, as indicated by 90 the presence of the gauge 15, and when the valve 16 is opened, some of the priming fluid 12, which is preferably gasoline, is forced out of the U tube 14, along the pipe 13, through valve 11 which was opened for 95 the purpose, along vaporizing pipe 5 into the intake 3, thereafter escaping at the slots 17 of the burners where the priming fluid is ignited and the vaporizing pipe 5 caused to be heated.

100 After sufficient heating of the vaporizing pipe 5, the priming valves 11 and 16 are closed and the fuel valves 18 and 10 opened. It should be observed that there is a minute orifice 19 at the bottom of the U tube 14, for 105 the purpose of admitting the priming fluid. Air enters the open end of the U tube, picking up the fluid in sufficient quantity to make a rich gas.

110 Resuming now the operation of the burner by use of the heavier oil. As stated before, the oil is forced along the pipe system by

means of pressure in the reservoir 7, and when this oil reaches the vaporizing pipe 5, it is turned into hydro-carbon gas by reason of the action of the heat thereon, the gas 5 then entering the intake 3 to be subsequently consumed at the places where it escapes out of the slots around the burners. Air mingles with the gas at the opening 6 of the intake 3, as can be plainly seen in Figure 3.

10 The burner structure comprises two or more burner rings, as illustrated in Figure 1. The conduit section of each ring is flanged as 20 at the ends, for the purpose of securing the burner parts together in the middle and to secure a mounting for the supporting plates 4 which carry the vaporizing pipe. These mounting plates 4 provide convenient means for fixing the burner to a stove in cases where the stove is not 15 large enough to fully accommodate the burner. In such cases, instead of fixing the burner on the inside, the ends thereof are projected out of the sides or rather ends of the stove, whereupon the mounting plates 4 are made use of to bolt or otherwise secure 20 the burner structure to the outside of the stove.

25 One of the intermediate flanges 20 is recessed at 21 to admit the slide 22 which is used for the purpose of cutting out or disconnecting the back burner 1 at the left in 30 Figure 1, should it be desired to employ only the burner at the right. This provision is one of convenience and economy, since 35 in cases where it is desired to use only one burner it naturally follows that there is a lesser consumption of fuel.

Adjustments of the flow of gas out of the nozzle 23 are made by means of the needle 40 valve 24. A rib 25, shown in Figure 5, runs lengthwise of the conduit 2 for the purpose of strengthening the burner structure so that there may be no undue sagging. A further detail of construction consists in 45 ribbing the under side of the stove lid 26 in Figure 9 for the purpose of strengthening the lid and preventing it from warping by the effect of the flame from the burners, but more particularly to facilitate heat 50 radiation.

The gas oven structure is shown particularly in Figures 6 and 7 wherein it is to be observed that the same burner structure, shown in Figure 1, is employed, all similar 55 reference characters indicating like parts. The slide valves between the various burner sets have rods 27 leading to the outside of the stove body 28, so that the slide valve 22 may be operated more conveniently. The 60 intake ends of the burners are clamped in suitable housings 29, which at once form supports for the upper ends of the burners and provide separate compartments from which air is introduced into the intakes 3.

65 However, these compartments may be

completely shut off by means of the slide valves 30, so that either very little air will be drawn in with hydro-carbon gas, or the burners will have to depend for their air supply from that which is normally present 70 in the compartment.

The oven 31 is jacketed at 32, the passage of heat from the burner structure in the oven being as indicated by the arrows, the products of combustion finally escaping at 75 the flue 33. Should it be found that the heat is too great for the oven, the large slide valve 34 in the back 35 of the oven, can be opened so that part of the heat passes directly into the stove compartment and from 80 thence out of the flue 33, instead of passing around the oven 31 as just stated and as indicated by the drawing.

A hinge connection 36 permits of swinging the oven down into the dotted line position in Figure 7, in cases where it is not desired to use the oven or when it is desired to obtain access to the burner structure for cleaning and adjustments. The oven burners are mounted in precisely the same manner as are the stove burners, there being a 85 separate compartment 29^a at the upper end in Figure 6, for the purpose of containing the intake 3^a. There is also a slide or gate valve 30^a for the purpose of regulating the 90 admission of fresh air.

While the construction and arrangement of the improved hydro-carbon gas burner as herein described and claimed is that of a generally preferred form, obviously modifications and changes can be made without departing from the spirit of the invention or the scope of the claims.

I claim:—

1. Fuel feeding apparatus, comprising 105 main and auxiliary containers of fuel under fluid pressure, the latter housing a U-tube with a submerged orifice to admit the fuel, and an opening above the surface to admit the pressure fluid; a burner, including communicating conduits and an entrance piece at one end of the conduits curved over into the direction of the top of the conduits, a vaporizing pipe connected to the main container, with means by which it is supported 110 in alignment above the conduit, including an adjustable nozzle directed into said entrance for the discharge thereinto of gas into which fuel oil in the pipe is converted; a pipe leading from the vaporizing pipe to the 115 auxiliary container, and a double valve for controlling the fuel pipes.

2. Fuel feeding apparatus, comprising a container of two fuels under fluid pressure, a U-tube in one fuel with an open end 125 above its surface to admit the pressure fluid, and provided with an orifice to admit said fuel during the passage of the fluid; a valve in connection with the U-tube, controlling the outflow of said fuel; and a valve body 130

in connection with said valve for controlling the flow of the other fuel into a burner. orifice, and an open end above the surface for the admission of fluid, and a burner with a double valve body with pipe connections 10 from the container and reservoir respectively.

3. Fuel feeding apparatus, comprising a container of relatively heavy fuel under fluid pressure, a communicating auxiliary reservoir of a lighter fuel, a U-pipe extending into said reservoir, having a submerged
